UNITED STATES PATENT OFFICE.

FREDERICK GRAF, OF NEW YORK, N. Y.

RULING DEVICE.

1,163,527.

Specification of Letters Patent.

Patented Dec. 7, 1915.

Application filed October 26, 1914. Serial No. 868,682.

To all whom it may concern:

Be it known that I, FREDERICK GRAF, a subject of the Emperor of Germany, residing at New York city, county and State of New York, have invented certain new and useful Improvements in Ruling Devices, of which the following is a full, clear, and exact specification.

This invention relates to ruling devices, and has for its object to provide a machine or tool of improved construction for ruling lines on various articles of stationery, such as account books, sheet paper, etc.

A further object is to provide improved means of adjusting the marking tool, and another object is to produce a tool capable of simultaneously ruling a plurality of lines of different thicknesses.

Other objects will become apparent as the description proceeds.

The invention will be first hereinafter described in connection with the accompanying drawings, which constitute a part of this specification, and then more specifically defined in the claims at the end of the description.

In the accompanying drawings, wherein similar reference characters are used to designate corresponding parts throughout the several views: Figure 1 is a front elevation of a ruling device constructed in accordance with my invention. Fig. 2 is a plan view thereof. Fig. 3 is a detailed plan view of the end portion of the sliding arm which fits in the T-shaped groove in the stand. Fig. 4 is a cross-section of the sliding arm taken through the slot which permits adjustment of the marking roller. Fig. 5 is a detailed view of a marking roller adapted for ruling two lines of different thickness, and Fig. 6 is a detailed view of another form of marking roller for ruling a different group of lines.

The machine or tool comprises a stand A of suitable length to extend parallel to the lines to be ruled, and an arm or carriage mounted to slide along said stand or support. The arm B is provided at one end with a T-shaped head C fitted to slide in a correspondingly shaped horizontal groove D in one side of the stand A. The extreme end portion of said arm B, which form the head of the T, is extended in both directions, as best illustrated at c in Fig. 3, for the purpose of steadyng the arm and preventing it from turning or twisting in the slot or

groove D during the movement of said arm along the stand in the operation of the device.

The arm B is provided with a T-shaped groove E opening along its under face, and fitted to slide in said groove are two brackets or yokes F and G, each having a T-shaped head H corresponding to the groove in the arm. The bracket or yoke F carries a supporting wheel K mounted transversely of the arm and designed for supporting the outer end of the arm substantially the same distance above the work as the other end of said arm is supported by the stand A. The bracket or yoke G carries the marking disk or roller L which may be tapered or V-shaped at its periphery, as shown in Figs. 1 and 2, for ruling a thin line. This roller or disk L is also mounted transversely of the arm and consequently parallel to the stand A. Ink or other marking material is fed to the disk L by a roller or pad M held in frictional contact with the upper portion of its periphery by a spring arm N best illustrated in Fig. 4.

Each of the brackets or yokes F and G are adapted to be clamped at different points along the arm B by set-screws P passed through slots R and S, respectively, in one longitudinal edge of the arm, and having shoulders p to clamp against the outer surface of said edge, the screws taking into the heads H of these brackets or yokes, as clearly shown in Fig. 4. The bracket or yoke F is adjusted according to the width of the work or the surface on which the work is supported, while the bracket G is adjusted according to the place where the line is to be ruled.

The operation of the device is very simple. The brackets F and G having been adjusted to meet requirements and clamped by means of the set-screws P at the proper points on the arm B, said arm is moved along the support A from one end of the work to the other, during which movement the marking roller L will be rotated by reason of its frictional contact with the surface of the work, and will transfer ink or other marking material from the pad M to such surface of the work through the instrumentality of the periphery of said marking roller or disk L. For convenient operation of the arm or carriage, a handle W may be mounted in any suitable manner thereon, preferably near its outer end.

As illustrated in Figs. 5 and 6, the form of the marking roller may be varied so as to simultaneously rule a plurality of parallel lines of the same or different thicknesses, the width of the line ruled depending upon the width of the periphery of the disk. In Fig. 5, the roller or disk L' is adapted to rule two lines close together, one line, a thin one, being marked by the sharp peripheral edge l , while a broader line is marked by the wider peripheral edge l' . The peripheral edges l and l' are separated by a groove l^2 , the width of which may be varied to determine the distance between the rulings. In Fig. 6, the adaptability this invention is further illustrated, the roller or disk L^2 there shown being adapted to rule five parallel lines, thin ones on either side and wider ones between. These thin lines are marked by the sharp peripheral edges l^3 , and the wider ones by the peripheral edges l^4 . Fig. 6 further shows how the distance between the rulings may be varied. It will be understood that the marking rollers L' and L^2 may be made integral or of a plurality of disks having peripheral edges of different widths and which may be carried in stock so that any desired selection may be made and combination made up by securing the selected disks together in any suitable manner.

Having thus described my invention what

Copies of this patent may be obtained for five cents each, by addressing the "Commissioner of Patents, Washington, D. C."

I claim as new and desire to secure by Letters Patent of the United States is:—

1. In a ruling device, the combination with a guide, of an arm movable along said guide and having a longitudinal groove T-shaped in cross section in one face and a slot in another face intersecting said groove, a marker having a head to fit and slide in said groove, and a set-screw passed through said slot and 35 engaging said head for clamping said marker at different points along said slot and groove.

2. In a ruling device, the combination with a guide, of an arm movable along said guide and having a longitudinal groove T-shaped 45 in cross-section in one face and two slots in another face intersecting said groove, a support having a head to fit and slide in said groove, a marker also having a head to fit and slide in said groove, and set-screws, one 50 passed through each of said slots and engaging one of the heads for clamping said marker and support at different points along said groove.

In testimony whereof I have signed my 55 name to this specification in the presence of two attesting witnesses.

FREDERICK GRAF.
